SOUNDING TOY FOR PET ANIMAL

Samuel Rosenberg, Brooklyn, N.Y., assignor to Excelsior
Pet Products, Inc., Brooklyn, N.Y.

Filed July 18, 1973, Ser. No. 380,269

Term of patent 14 years

Int. Cl. D21—01

U.S. Cl. D34—15 A

FIG. 1

FIG. 2

FIG. 3

FIG. 1 is a side-elevational view of a sounding toy for pet animal embodying my new design;

FIG. 2 is a right end view thereof; and

FIG. 3 is a side-elevational view of FIG. 1 turned at an angle of 90°.

I claim:

The ornamental design for a sounding toy for pet animal, as shown and described.
